United States Patent Office

Des. 226,635
Patented Apr. 3, 1973

226,635

HYDROTHERAPY APPARATUS

Clifford E. Grube, Niles, Ill., assignor to
Associated Mills, Incorporated

Filed Mar. 27, 1972, Ser. No. 238,751

Term of patent 14 years

Int. Cl. D24—04

U.S. Cl. D83—1 T

FIG. 1

FIG. 2

FIG. 3

FIG. 4

FIG. 5

FIG. 7

FIG. 8

FIG. 1 is a front perspective view of the hydrotherapy apparatus of the present invention;

FIG. 2 is a rear perspective view thereof;

FIG. 3 is a bottom plan view of the hydrotherapy apparatus of the present invention;

FIG. 4 is a top plan view thereof;

FIG. 5 is one end view thereof;

FIG. 6 is one side view thereof;

FIG. 7 is the other end view thereof; and

FIG. 8 is the other side view thereof.

I claim:

The ornamental design on a hydrotherapy apparatus, as shown and described.
